UNITED STATES PATENT OFFICE

146,160

DESIGN FOR A SHOE

Morris Wolock, New York, N. Y.

Application September 4, 1945, Serial No. 121,821

Term of patent 3½ years

(Cl. D7—7)

To all whom it may concern:

Be it known that I, Morris Wolock, a citizen of the United States, residing at New York city, in the county and State of New York, have invented a new, original, and ornamental Design for a Shoe, of which the following is a specification, reference being had to the accompanying drawing, forming part thereof.

Fig. 1 is a side elevation of a shoe, showing my new design.

Fig. 2 is a top plan view thereof.

Fig. 3 is a partial sectional view taken substantially on line 3—3 of Fig. 1, the sole portion being shown in diagrammatic outline.

I claim:

The ornamental design for a shoe, substantially as shown and described.

MORRIS WOLOCK.
